UNITED STATES PATENT OFFICE.

EDWARD A. JOHNSTON, OF CHICAGO, ILLINOIS, ASSIGNOR TO INTERNATIONAL HARVESTER COMPANY, OF CHICAGO, ILLINOIS, A CORPORATION OF NEW JERSEY.

HARVESTER PITMAN CONNECTION.

SPECIFICATION forming part of Letters Patent No. 730,022, dated June 2, 1903.

Application filed September 18, 1902. Serial No. 123,904. (No model.)

To all whom it may concern:

Be it known that I, EDWARD A. JOHNSTON, a citizen of the United States, residing in the city of Chicago, county of Cook, State of Illinois, have invented certain new and useful Improvements in Harvester-Pitmen Connections; and I do hereby declare the following to be a full, clear, and exact description of the invention, such as will enable others skilled in the art to which it appertains to make and use the same.

This invention relates to pitmen connections, and pertains more particularly to connecting devices to be employed in coupling the reciprocating pitmen to the knife-heads of harvesters, mowers, and the like.

The object of my invention is to provide a pitman connection that may be quickly operated to couple and uncouple the coöperating parts without the use of tools and that will automatically take up the wear between the journal of the pitman and the knife-head without allowing any yield in the connection in the line of the thrust of the pitman.

The invention is illustrated in the accompanying drawings, in which—

Figure 1 is a plan view of the knife-head and pitman with my invention applied thereto. Fig. 2 is a sectional view showing the pitman removed from the knife-head and the connector in released position. Fig. 3 illustrates the construction of the tapered hook-shaped end of the pitman. Fig. 4 is a horizontal sectional view of the knife-head bearing and the connector, showing the pitman and knife-head coupled in operative relation. Fig. 5 is a corresponding view showing the manner of releasing the connector. Fig. 6 is a perspective view of one-half of the connector.

Referring to the drawings, reference character *a* indicates a knife-head of a type ordinarily employed in harvesters, mowers, and the like, which knife-head is provided with the usual circular bearing *b*, by which the knife-head is connected with the reciprocating mechanism. The pitman *c*, which is connected to the knife-head to reciprocate the latter, is provided at its forward portion with a lateral projection or hook-shaped end *c'*,

two faces of which are tapered or beveled, as clearly indicated in Figs. 2 and 3.

In order to provide a journal for the pitman as thus constructed, which journal will find an easy and self-adjustable bearing in the knife-head, I construct a connector of two similar sections *d d*, which are provided with approximately semicylindrical bearing-surfaces *d' d'* at their outer ends, which surfaces are bounded by lateral flanges *d''*. Said sections *d d* are preferably hinged at their lower ends, as at *d''*, and each or either section is provided with a lateral orifice *d⁴*, passing through the same, beyond which orifice the inner face of the section is furnished with a tapered or beveled depression or recess *d⁵*. The lower end of each section has a semicylindrical recess *d⁶*, which recesses coöperate when the sections are brought together to form a seat for a spiral spring *e*.

The normal operative relation of the several parts of the apparatus described above is illustrated in Figs. 1 and 4, in which the tapered head *c'* of the pitman *c* occupies the tapered recess formed by the two sections *d d* of the connector, the journal end of which occupies the bearing *b* of the knife-head and is held in close contact therewith by the wedging action of the coöperating tapers on the pitman end and the inner surfaces of the journal-sections. The tapered hook-shaped end of the pitman is held firmly within the recess of the connector-sections by means of a spiral spring *e*, which bears upon the side of the pitman opposite the hook-shaped end and rests within the cup-shaped depression formed by the recess *d⁶*.

To apply the connector as above described to its intended use, the hook-shaped end *c'* of the pitman *c* is threaded through the lateral opening *d⁴* in one of the connector-sections and turned until the tapered end *c'* thereof occupies the tapered recess formed between the mating coupler-sections, while the spring *e* is compressed between the side of the pitman and the hinged end of the coupler. The hook-shaped end of the pitman is then forced toward the hinged end of the coupler, and the sections of the coupler are compressed or brought together, as indicated in Fig. 5, until

the flanges d^2 on the upper end of the sections will pass freely through the bearing b in the knife-head. The coupler is then threaded through the bearing b until said flanges d^2 pass beyond the edge of the bearing, after which the lateral pressure upon the coupler-sections is released and spring e forces the hook-shaped end c' into the forward tapered recess of the coupler, with the result that the tapered sides of the hook-shaped pitman end force the journal-sections apart until the flanges d^2 overlap both edges of the bearing b and the journal-sections d' of the coupler fit snugly within the said bearing. The spring e , constantly reacting between the pitman and the end of the coupler, holds the tapered pitman end firmly up to its work, and it will be noted that any wear between the journal and the bearing b will be immediately taken up by the wedging action of the pitman end forcing the coupler-sections farther apart.

It will be noted that the connection is adapted to be quickly applied to or removed from the bearing of the knife-head without the use of special tools; also that the connection is preferably rigid in the line of the pitman and allows no yield whatever in response to its thrust. To remove or release the connections, it is only necessary to withdraw the hook-shaped end c of the pitman from its engagement with the tapered recess between the coupler-sections by moving the end of the pitman against the tension of the spiral spring e and then forcing the journal ends of the sections toward each other until the outer flanges d^2 thereof clear the inner edges of the bearing b , after which the coupler may be pulled through the bearing b , as indicated in Fig. 5. The coupler may then be removed from the pitman end for adjustment or repair, after which it may be readily and easily applied again to its intended use by an unskilled workman without the use of special tools.

Having thus described my invention, what I claim is—

1. A pitman connection, comprising a longitudinally-divided journal having a tapered recess between the sections thereof, a pitman having a tapered end, and means to retain the tapered pitman end in engagement

with the recess, whereby the journal is expanded within its bearing.

2. A pitman connection, comprising a longitudinally-divided journal, having a tapered recess between the sections thereof, a pitman having a tapered end, and a spring interposed between the journal and the pitman end to force the tapers of the journal-sections and the pitman end together, whereby said journal is expanded within its bearing. 60

3. A pitman connection, comprising an expandable journal formed of two sections, pivoted together at one end, and provided with a tapered recess at the other, a pitman having a tapered hook-shaped end engaging the recess between the pivoted sections, and a spring located between the pitman end and the pivoted end of the journal, whereby the tapered pitman end is forced within the recess in the journal to expand the sections. 70

4. A pitman connection, comprising an expandable journal formed of two sections, pivoted together at one end, and provided with a tapered recess at the other, there being flanges on the respective sections adapted to 75 retain the journal within the bearing, a pitman having a tapered hook-shaped end on the pitman engaging the recess between the pivoted sections, and a spring interposed between the pitman end and the pivoted end of 80 the journal to force the pitman end within the recess and expand the journal within the bearing.

5. A pitman connection, comprising a longitudinally-sectional journal, having a tapered 85 recess between the sections, a pitman having a corresponding tapered end, and a spring normally forcing the end of the pitman into the tapered recess to take up wear, the recess, the pitman end and the direction of the 90 reaction of the spring being in a line transverse to the pitman so as to prevent yielding of the connection in response to the thrust of the pitman.

In testimony whereof I affix my signature 95 in presence of two witnesses.

EDWARD A. JOHNSTON.
